UNITED STATES PATENT OFFICE.

ARTHUR J. FISH, OF EAST ROCHESTER, NEW YORK.

WINDOW-CLEANER.

1,088,653.

Specification of Letters Patent.

Patented Feb. 24, 1914.

Application filed May 12, 1911. Serial No. 626,689.

To all whom it may concern:

Be it known that I, ARTHUR J. FISH, a citizen of the United States, residing at East Rochester, in the county of Monroe and State of New York, have invented new and useful Improvements in Window-Cleaners of which the following is a specification.

This invention relates to window cleaners and the object of the invention is to provide a simple and cheaply constructed device of this character which may be readily and conveniently attached to a sash and particularly to the sash of vestibule shields on trolley cars and the like, so as to clean the front 15 of the window from the inside.

Further objects of the invention will appear as the following specific description is read in connection with the accompanying drawing, which forms a part of this application, and in which:—

Figure 1 is a front elevation of a sash showing my improved cleaner attached thereto. Fig. 2 is a detail rear elevation. Fig. 3 is a detail vertical sectional view.

Referring more particularly to the drawing, 1 and 2 represent the top and bottom sills of the sash and 3 and 4 represent the side stiles thereof. Mounted in the bottom sill, centrally of its length, is a bearing member 5 in which a shaft 6 is journaled, said shaft having squared ends 7. The outer squared end has secured thereon, by means of a cotter pin 8, a crank arm 9 whose outer end is bent at right angles to the normal line 35 of the arm and in normal position extends up parallel with the stile 4. The terminal end of this portion is bent at an obtuse angle, as shown at 10, and pivoted to the terminal end is a cleaning strip 11 which is 40 adapted to operate over the glass 12.

Secured to the inner end of the shaft 6, by means of the cotter pin 13, is a crank arm 14 having a handle 15 projecting at right angles thereto. When the crank arm 45 14 is raised the end 10 of the crank arm, with its cleaning strip, will be carried across

the glass 12 so as to clean the same. When the crank arm is returned to normal it lies parallel with the bottom sill of the sash and the parts of the arm 9 lie parallel with the bottom rail and the stiles with the cleaning 50 strip 11 lying against the stile 4.

It will be seen from the foregoing that all that is necessary to do to the sash is to drill a hole in the bottom rail and place the device thereon by first attaching the bearing, 55 inserting the shaft and keying the crank arms 9 and 14 thereto.

When in its normal position the weight of the crank arm 9 and the handle crank 14 serves to hold the cleaning strip 11 in an 60 inoperative position as shown clearly in Fig. 1, and the outer end of said crank arm 9 normally out of the plane of the window pane and when operated is adapted to move the cleaning strip 11 across the window panes 65 in a very slight arc.

Having thus described the invention, what I claim as new is:—

In a window cleaner, a sleeve adapted to be fitted in the bottom rail of a sash, a shaft 70 rotatably mounted within said sleeve having squared ends, a right angular arm mounted upon one end of said shaft adapted to lie in a position parallel to the sill and one of the stiles of a sash, the vertical portion of said 75 right angular arm being curved inwardly at its upper end, a cleaning strip pivoted to the inwardly curved portion and a crank arm provided with a handle mounted upon the inner end of the shaft and extending therefrom in the same direction as the lower portion of the angular arm, to move the cleaning strip in a slight arc across the window pane.

In testimony whereof I affix my signature 85 in presence of two witnesses.

ARTHUR J. FISH.
